PORTABLE FAN

Adolf P. C. Schramm, New York, N. Y.

Application October 6, 1931. Serial No. 567,185

8 Claims. (Cl. 230—117)

This invention is a novel portable fan, or an electrically driven portable mechanism for maintaining air circulation within a room and performing certain allied functions as will be described.

The main object of the present invention is to afford an improved portable or table fan embodying adjustments of action or air flow to enable a better utilization thereof. A particular object is to afford an improved arrangement of a horizontal fan of the blower type, with driving motor beneath and air inlets above, or vice versa. A further object is to provide a plural number of air discharge slots or outlets which are separately adjustable in regard to the size or width of the discharge outlet, the force or velocity of the delivered stream of air, and the direction of delivery; particularly to provide for the selective adjustment of the several outlets so that some may be closed while others are open, according to the needs, and so that one or more of them may be relatively tilted upwardly or downwardly with respect to the normal direction of delivery.

Other and further objects and advantages of the present invention will be explained in the hereinafter following description of an illustrative embodiment thereof or will be understood to those conversant with the subject. To the attainment of such objects and advantages the present invention consists in the novel table fan, and the novel features of operation, combination, construction and detail herein illustrated or described.

In the accompanying drawings Figure 1 is a side elevation of a table fan resting portably upon a table and embodying the several features of the present invention.

Fig. 2 is a top plan view of the fan shown in Fig. 1 with certain parts broken away to show the construction beneath.

Fig. 3 is a central vertical section of the fan shown in Figs. 1 and 2.

Fig. 4 is a horizontal section taken on the line 4—4 of Fig. 3 looking from above.

Fig. 5 is a vertical section taken on the line 5—5 of Fig. 3 looking from the interior.

Fig. 6 is a wiring diagram showing a convenient hook-up for the fan driving motor and the air heating units of the apparatus.

Referring to the illustrated details of construction, the fan of this invention is shown as comprising a hollow base 10 adapted to rest upon a table, desk or the like, and upstanding above the base a hollow casing in the general form of a

column within which is contained the drive mechanism as will be described. Continuing the description of the parts seen from the exterior, as in Figs. 1 and 2, above the hollow column 11 are shown first the lower wall portion 12 of the fan chamber and thereabove the upper wall portion 13 of the same. The wall 12 may either be fitted to the top end of the hollow column, or formed integrally therewith, while the upper wall 13 is constructed separate from the wall 12, these being brought together in assembly after the assembly of the interior mechanism. Above the upper chamber wall 13 is shown an enclosing cover 14, which is preferably a separate element assembled during manufacture. Above the cover is shown a cylindrical extension 15 in the form of a cupola and which may be employed as a water vessel for humidifying purposes, this being closed at the top by removable cap 16.

Referring to the interior parts, and commencing at the base, a set of fixed brackets 19 is shown giving support to a rheostat or controller 20 having a handle or lever 21 by which the rheostat may be adjusted to vary the speed of the motor and fan.

Within the upper part of the hollow column 11 are shown fixed brackets 24 giving support to an electric motor 25 which as usual may comprise the fields 26 and armature 27, the latter having a central vertical axis.

The shaft of the motor 25 is shown extended at 29 and at its upper end carrying a blower fan comprising a horizontal disk 30 with upstanding blades 31. The fan thus constructed draws air down centrally from above and throws it centrifugally outward in a generally horizontal direction.

Conveniently the water regulating means for air moistening purposes may now be described. The hub or central part of the fan disk 30 is shown as having an upward extension 33 with a central projection or teat in the form of a cone at the top thereof. At the foot of the cone, attached to the hub, is a hold-down or plate 35 forming a circular recess or groove in which may be accommodated a non-rotating disk or plate 36 from which connections extend to the water regulating valve.

The vessel 15 may contain a supply of water as shown. In the bottom wall of the vessel is shown a conical seat and outlet 37, normally closed by the conical lower end of a valve needle or rod 38. The needle valve rod or spindle may be movable vertically within fixed slideways 39 arranged centrally within the vessel. The vessel

also may contain fixed vertical guides 40 near the opposite sides, and within these guides vertical rods 41 capable of sliding up and down for actuating the valve.

- 5 The valve actuating rods 41 extend through the vessel bottom and at their lower ends are cross-connected by the plate or disk 36. At their upper ends, within the vessel, the rods are connected by a head or bar 42, which head has a 10 loose engagement around the valve needle or spindle 38. The rigid frame thus formed by the plate 36, the head 42 and the two rods 41, is adapted to be adjusted upwardly and downwardly and this movement may be performed by the 15 bodily vertical shifting movements of the fan 30, 31 produced in turn by the bodily movements of the motor armature which shifts upwardly and downwardly between different floating positions in the motor as will be more fully described.
- 20 While the cross-head 42 loosely surrounds the valve spindle 38 it is arranged to actuate the latter as follows. Normally, when the apparatus is idle the valve is closed and the cross-head is in its lowermost position, as shown in Fig. 3. A 25 stop 43 is shown in the form of a pin extending through the spindle slightly above the cross-head so that when the latter starts to rise it contacts the stop and thereafter lifts the valve spindle. Preferably a spring is interposed between the 30 spindle and cross-head, for example a tension spring 44, arranged to pull down upon the spindle so as to hold the valve closed when the apparatus is idle, and so as to hold the stop 43 in contact with the cross-head 42 during operation.
- 35 The arrangement gives four different adjustments to the needle valve corresponding to the four different positions of the motor armature as indicated by the dotted lines in Fig. 3. The feed of water is thus roughly proportioned to the speed 40 of the fan. The needle valve allows the water to descend drop by drop, at varying speeds, upon the teat 34, which may split each drop, the water spreading over the surface of the hold-down plate 35 and being rapidly picked up by the descending intake air, vaporized, and thrown out 45 horizontally with the air delivered by the fan.

The air is taken in through the cover 14, which for this purpose is shown formed with a series of damper openings 46. The action of the fan can 50 be regulated to advantage by adjustment of the inlet openings 46, and for this purpose a damper disk 47 is shown at the under side of the cover, subject to rotation by a handle 48.

The warming of the delivered air is herein effected by an arrangement of resistance wires 55 50 located in the intake, preferably immediately beneath the cover 14. No air therefore can get into or be delivered from the fan without being subjected to the warming action of the heating elements. This arrangement has the further advantage that, when the air is both to be warmed and moistened, the preliminary warming of the air assists greatly in picking up the moisture delivered by the needle valve.

60 The resistance wire 50 may be arranged in different forms, but as seen in Figs. 2, 3 and 6 it is stretched across the annular space surrounding the water vessel, namely between inner supporting hooks 51 mounted on an insulated ring 52 and outer supporting hooks 53 mounted on an insulated ring 54.

Having described the electric parts of the apparatus, the circuits in Fig. 6 will now be referred to. The motor 25 with its field coils 26 and armature 27 is diagrammatically shown. The sup-

ply of electric current is indicated by a generator G and from the generator extends a circuit g to the motor and to the rheostat 20 shown as comprising resistance wire between switch points. Four switch points are shown, a, b, c 80 and d. When the switch lever 21 is at position a all current is cut off, the speed is zero, and the armature takes its lowest position as shown in Fig. 3. When the switch lever 21 is shifted to point b the circuit is closed for minimum current and speed of motor, and as well understood the interaction between field and armature lifts the armature from its bottom position a to a higher position b as indicated in dotted lines in Fig. 3. When the lever is shifted 90 to position c a medium current and speed are afforded and the armature lifts to position c. When the lever is thrown into position d the maximum current and speed are afforded and the armature rises to its topmost position d. In 95 positions b, c and d the armature and fan are in floating condition, dispensing with thrust bearing at the foot of the shaft, and each of these three positions gives an open adjustment of the needle valve, the water delivery thereby being 100 regulated in accordance with the speed of action.

The heating coil 50 is connected in a circuit g' paralleling the motor and this circuit may include a toggle switch g² by which the current can be permanently cut off. An arrangement is 105 shown in Fig. 6 whereby the heating current is cut off with the stopping of the fan. Behind the switch lever 21 is an auxiliary switch lever 56 shown in the zero or a position. When the two levers are shifted to the first operating position 110 d the circuit is closed to the resistance wire through the lever 56 and a separate contact at d. The auxiliary lever is yieldingly connected to the switch lever by a spring 57. The auxiliary lever comes against a stop 58 holding it there, 115 with the circuit closed through the heater coil, unaffected by further movement of the switch lever. Whenever the switch lever 21 is thrown to stop the motor this restores lever 56 and cuts off the current from the resistance elements. 120 The circuits thus illustratively shown may be varied and embodied in many different physical arrangements. By dispensing with lever 56 and controlling both circuits by lever 21 the degree of heating of the coil 50 will be varied with the 125 motor speed if desired.

The air discharge from the fan is horizontally outward through a number of discharge openings 60 formed in the chamber walls 12 and 13. Four such discharged openings are shown, but there 130 might be three or five or other plural number. Attached within the casing or wall at each corner, or between each two discharge openings, is shown an angle piece or casting 61, one side of which forms a supporting bracket for one of the discharge control means to be described, the other side constituting a bracket for the adjacent discharge means. Extending across from one bracket 61 to another, within each discharge opening 60, is certain mechanism directing and 135 controlling the outflow of air. One of these elements is what may be termed a rotary air box or discharge duct 62, having end pieces 63 and 64 at the left and right as seen in Figs. 3, 4 and 5. These end pieces are adapted to rotate on their 140 brackets, and the rotary air box is completed by outwardly converging top and bottom walls 65, which may be curved as shown in Fig. 3, and cut away at their outer corners to accommodate certain other parts. At its left end each rotary air 145 150

box is supported upon its bracket by a pivot stud 67 and at the other end is shown a right pivot stud 68, these two studs being suitably secured to the rotary box so as to turn with it. Each end piece 63 or 64 may be substantially circular, and hold-down plates or angles 69 may be arranged to confine their inner sides.

Each rotary air box may be rotated to a limited extent to change the direction of delivery of air by tilting the same upwardly or downwardly. The following means may be employed for this adjustment. The right-hand pivot stud 68 is shown as extended through the wall of the bracket or angle piece 61 and there enlarged into an exterior head or fork 71. A rod 72 is shown extended through the two sides of the fork this rod extended outwardly and formed with a knurled head or handle 73. These handles appear in the exterior views of Figs. 1 and 2 as well as in Figs. 3 and 4. Any one of the four handles may be independently swung up and down to rotate the pivot stud and the air box, thereby directing the air stream either horizontally or at a desired upward or downward tilt. When used on a desk or table the air therefore may be varied in direction to suit the convenience or comfort of the user.

The same handle 73 and rod 72 are employed for the control of a pair of louvers to be described, mounted on each rotary air box 62. The rod 72, between the sides of the fork 71, is provided with a collar 74 clamped to the rod, preventing endwise play but permitting rotation. The extremity of the rod is threaded at 75 and this thread is engaged in a threaded aperture in a stud or head 76, so that by turning the knurled head 73 the stud 76 is thrust longitudinally. The stud 76 is shown extending inwardly through a cutaway recess of the angle piece 61, and at the inner side of the angle piece the stud is extended as a threaded pin 77 carrying lock nuts for confining on the pin a pair of links 78. A face view of these parts is seen at the left side of Fig. 3. The links 78 extend from the radially moving stud or pin 77 to an upper bail or U-shaped strip 80 and a similar lower bail 81, both bails pivoted on the same pivot studs 67 and 68 which carry the rotary air box. The two blades in turn carry respectively an upper louver 82 and a lower louver 83.

By this arrangement the turning of the knurled head 73 causes the links to operate the bails and louvers to swing the latter more or less toward or from each other. Thus at the left side of Fig. 3 the louvers are swung fairly close together, affording a narrow and forcible air stream, which also is directed horizontally outward. At the other or right side the knurled handle has been turned to adjust the louvers to a wide open position, giving an increased flow but reduced velocity of air; and for illustration the air box at this side has been shown tilted upwardly by the handle 73. Each handle therefore readily gives the two adjustments, namely of the tilted angle of discharge, and of the width of discharge passage or slot, between maximum opening and closed position.

The water supply regulation means described is illustrative of the principle involved, and may be replaced by an electric solenoid control, adjusting the valve according to the fan speed; or a centrifugal governor would serve; or the water by its own centrifugal force could be caused to flow in quantities variable with the speed of the fan through restricted passages for delivery to the air streams.

75 There has thus been described a portable fan

embodying the principles and attaining the objects of the present invention. Since many matters of operation, combination, construction and detail may be variously modified without departing from the principles it is not intended to limit the invention to such matters except so far as set forth in the appended claims.

What is claimed is:

1. A portable or table fan having a motor-driven vertical shaft carrying a fan disk and fan blades affording centrifugal air delivery and a casing within which the fan rotates having air intake opening above the fan and a plurality of separate air discharge openings at the periphery; and characterized by a delivery box bodily tilt- 85 able to vary the discharge direction, and having upper and lower wall parts forming each discharge opening between them as a horizontal slit with manual means to tilt upward or downward said delivery box for adjusting the direction of discharge.

2. A portable or table fan having a motor-driven vertical shaft carrying a fan disk and fan blades affording centrifugal air delivery and a casing within which the fan rotates having air 100 intake opening above the fan and a plurality of separate air discharge openings at the periphery; and characterized by a delivery box at each discharge opening presenting a horizontal discharge slit, with means to regulate the width 105 of such slit, and means to tilt the delivery box upwardly and downwardly.

3. A portable fan as in claim 2 and wherein for each discharge opening is a single handle 110 with connections both for regulating the width of discharge slit and the upward or downward tilt of discharge.

4. A ventilating fan comprising fan blades affording centrifugal air delivery, and a casing having an air intake opening and having one or more air discharge openings at the periphery; and characterized by an interior delivery box 115 bodily tiltable to vary the discharge direction at each opening, and having outer wall parts forming each discharge opening between them as a horizontal slit, with means to tilt upward or downward each delivery box for adjusting the direction of discharge.

5. A ventilating fan comprising a housing with an air inlet and one or more peripheral 125 apertures for centrifugal air discharge, and a control means for each such discharge consisting of an interior delivery box comprising upper and lower walls forming a discharge chamber between them and bodily tiltable to vary the discharge direction.

6. A ventilating fan comprising a housing with an air inlet and one or more peripheral apertures for centrifugal air discharge, and a control means for each such discharge consisting of an interior delivery box comprising upper and lower walls forming a discharge chamber between them and bodily tiltable to vary the discharge direction; and outer wall parts for each box forming 135 between them a horizontal discharge slit.

7. A ventilating fan comprising a housing with an air inlet and one or more peripheral apertures for centrifugal air discharge, and a control means for each such discharge consisting of an interior delivery box comprising upper 145 and lower walls forming a discharge chamber between them and bodily tiltable to vary the discharge direction; and outer wall parts for each box forming between them a horizontal discharge slit, and means for adjusting said outer 150

wall parts to regulate the width of the discharge slit.

8. A ventilating fan comprising a housing with an air inlet and one or more peripheral apertures for centrifugal air discharge, and a control means for each such discharge consisting of an interior delivery box comprising upper and lower walls forming a discharge chamber between them and bodily tilttable to vary the discharge direc-

tion; and outer wall parts for each box forming between them a horizontal discharge slit, and means for adjusting said outer wall parts to regulate the width of the discharge slit; with a single handle or controller having connections both to the box or for regulating the tilt of the discharge and to the wall parts for regulating the width of the discharge slit. 80
